(57) **CLAIM**

The ornamental design for a wearable display system, as shown.

DESCRIPTION

FIG. 1 is a perspective view of the wearable display system as worn by the user;

FIG. 2 is a left side view of the wearable display system of FIG. 1 without the screen portion and without the human wearer;

FIG. 3 is a right side view of the wearable display system of FIG. 1 without the screen portion, without the screen support and without the human wearer;

FIG. 4 is a rear view of the wearable display system shown in FIG. 3;

FIG. 5 is a front view of the wearable display system shown in FIG. 1;

FIG. 6 is a rear view of the wearable display system of FIG. 2;

FIG. 7 is a left side view of the wearable display system of FIG. 1 without the human wearer;

FIG. 8 is a rear view of the wearable display system shown in FIG. 1; and,

FIG. 9 is a rear view of the wearable display system shown in FIG. 1 without the human wearer.

The portion of the figures shown in dotted lines are hereby disclaimed.

In FIGS. 2,3,4 and 6 elements have been shown separately for ease of illustration only.

The design is the shape of the wearable display system shown in the drawings.
